JOSEPH A. RUFF, OF CAMBRIDGE, ASSIGNOR TO THE METALLIC COMPRESSION CASTING COMPANY, OF BOSTON, MASSACHUSETTS, ASSIGNOR TO RUSSELL & ERWIN MANUFACTURING COMPANY, OF NEW BRITAIN, CONNECTICUT.

Design No. 4,110, dated June 7, 1870.

DESIGN FOR A BELL-PULL KNOB.

The Schedule referred to in these Letters Patent and making part of the same.

I, JOSEPH A. RUFF, of Cambridge, in the county of Middlesex and State of Massachusetts, have invented and produced a new and original Design for a Bell-pull Knob, of which the following is a specification.

The nature of my design is represented in the accompanying photographic illustration, to which reference is made.

I claim the design for a bell-pull knob, substantially as above set forth.

JOSEPH A. RUFF.
